UNITED STATES PATENT OFFICE.

SAMUEL D. FORBES, OF WILMINGTON, DELAWARE.

IMPROVEMENT IN METALLIC HUB-BANDS.

Specification forming part of Letters Patent No. 124,202, dated March 5, 1872.

SPECIFICATION.

To whom it may concern:

Be it known that I, SAM'L. D. FORBES, of the city of Wilmington, in the county of New Castle and State of Delaware, have invented a new and useful Improvement in Metallic Bands for Wagon-Hubs; and I do hereby declare that the following is a full and true description thereof, reference being had to the accompanying drawing and to the letters of reference marked thereon.

The object of my invention is not only to produce neater shape and a saving of material, but to overcome a very serious defect in devices of this kind having flanges or projections extending upon the body of the spokes, especially in hubs with "staggering" mortises, as will be more fully hereinafter described.

In the accompanying drawing, Figure 1 is an elevation, and Fig. 2 a longitudinal section of Fig. 1.

Similar letters of reference indicate corresponding parts.

A is the ordinary wooden hub, constructed with staggering mortises. B is a metallic band, with staggering mortises to correspond with those in the wooden portion, the mortises in

the band being made slightly larger to receive the body of the spoke, the distance upon the body of the spoke the band extends being limited to the thickness of the band. This band is made slightly tapering on its interior surface to insure a tight fit when driven or shrunk upon the wooden portion.

The very serious objection of chafing, as in the case of metallic bands having projections extending upon the body of the spokes, is entirely overcome by my improved band. This chafing is produced by the "working" of the wheel, and for the reason that more motion exists at this point than at the base. My improved band supports the body of the spokes at that portion of the body of the spokes where the least motion exists, thereby producing a new function and entirely preventing the very serious objection of chafing, especially in hubs with staggering mortises.

Having thus fully described my invention, as a new article of manufacture, I claim—

The metallic hub-band B, substantially as described, and for the purpose specified.

SAMUEL D. FORBES.
